UNITED STATES PATENT OFFICE.

WALTER ROYSTONE, OF FORT WORTH, TEXAS, ASSIGNOR TO M. P. EXLINE, OF DALLAS,
TEXAS, INDEPENDENT EXECUTOR OF A. S. EXLINE, DECEASED.

PASS-BOOK.

1,168,966.

Specification of Letters Patent. Patented Jan. 18, 1916.

Application filed June 24, 1914. Serial No. 847,113.

To all whom it may concern:

Be it known that I, WALTER ROYSTONE, a citizen of the United States, residing at Fort Worth, in the county of Tarrant and State of Texas, have invented certain new and useful Improvements in Pass-Books; and I do hereby declare the following to be a full, clear, and exact description of the invention, such as will enable others skilled in the art to which it appertains to make and use the same.

This invention relates to book binding, and more especially to covers; and the object of the same is to produce a pass book whose cover may be externally rough and its surface of a character which will not readily receive writing, with a panel depressed into the face of the cover and so surfaced that it will readily take writing fluid. This object is carried out in a number of ways whereof certain embodiments are set forth in the following specification and shown in the drawings in which:—

Figure 1 is a front elevation of a pass book or deposit book, such as is used in banks, the front cover thereof being provided with my invention; and Fig. 2 is a central vertical section through a portion of said front cover on the line 2—2 of Fig. 1, this view being on an enlarged scale. Fig. 3 is a horizontal section of another plan for carrying out the same general idea, and Figs. 4 and 5 are fragmentary horizontal sections of yet other plans and on a slightly larger scale. Fig. 6 is a horizontal section through a complete pass book provided with my invention by means described below. Fig. 7 is a fragmentary section of yet another manner of carrying out the invention.

By the term "pass book" herein I refer to any book whose size is such that it is usually carried in the pocket and whose use is such that it is frequently drawn forth for the reception of important memoranda. We may assume that the pass book referred to is a deposit book such as is used by banks for crediting their customers with the amounts deposited. As these books are often carried in the pocket of the working man, or of any person where they are subjected to considerable wear against adjacent objects and where they possibly sometimes

become damp from perspiration or other sources, they are securely bound in a cover which is usually embossed on its outer face as by being pebbled, grained, or otherwise rendered rough, or perhaps by being made of leather or other material or composition of materials upon which it is somewhat difficult to write with the pen and ink or from which such writing soon wears off. Ordinarily the name of the bank is printed on the front cover, together with the words "In account with," and below the latter is written the name of the depositor. In this specification we are not concerned with what is printed or written upon the pages of the leaves of the book, but when anything is written on an exposed face of the cover it is subjected to wear as has been suggested, and is soon obliterated by abrasion or from other causes. If the name or other matter so written on the cover is not duplicated on the pages of the book, confusion arises which sometimes results in disagreements or losses.

It is the purpose of the present invention to provide on a cover which is otherwise rough or in any event a poor writing surface, a panel which is itself faced with something which is a good writing surface and will retain the ink; and in the preferred embodiment of my invention the front face of the panel is depressed below the surrounding portion of the front face of the cover so that—if the panel be not too large—the contact of the cover with contiguous objects in the pocket prevents the contact of such objects with the face of the panel.

Heretofore it has been proposed to cut an opening in the cover through which an inner sheet or card is visible, and write on the face of such card which is exposed through the opening; but I find that when the cover is cut in any way it is weakened, no matter if the card be lapped well over the edges of the opening and carefully secured inside the cover. It is undesirable to weaken the cover, especially in books which are to be carried in the pocket and handled often, and accordingly I employ other means for forming these panels.

In the drawings hereto annexed the cover has a rear leaf R and an unbroken

front leaf or face F, and the leaves L of the book are bound into the cover at B. I will describe my invention as employed in connection with a deposit book or pass book as used in banks. As seen in Fig. 1 the front cover is printed at N with the name of a bank, beneath which appears the words "In account with" and beneath these words in turn is a space or panel P in which is to be written the name of the depositor in accordance with the practice now in common use. As shown in this view also the face of the cover F is pebbled, and ordinarily this face does not readily receive writing. The panel P is shown in Fig. 2 as being formed by stamping a depression 1 into the front face of the cover, which should be carefully done so that the cover is not broken or cracked. This will naturally make the material of the cover a little denser at 2 behind the panel. Next I insert into said depression a thin sheet 3 of some material which offers a good writing surface, the sheet being of such consistency that it will itself adhere to the cover on being printed or impressed in the bottom of its depression 1, or the sheet may be pasted onto the bottom of said depression as indicated by the word "Adhesive" in Fig. 5. In any event the face 5 of the sheet 3 stands in a plane slightly within or behind that of the face 6 of the cover F so that adjacent objects which lie against the face of the cover will not touch the face of the sheet. In Fig. 2 the edges of the depression which form the outline of the panel are rather abrupt as shown at 7. This panel may be stamped into the cover material F at the time the cover is cut by a die or otherwise, but the means for forming the panel and for applying the sheet 3 constitute no part of the present invention.

In Fig. 3 I have used the same reference numeral to indicate the sheet, and it may adhere directly to the cover F or be pasted or glued thereon as before; the edges 8 of the panel are beveled so that they are not as abrupt as elsewhere shown, or in other words the stamping is done in such manner that the material of the cover is not made denser as at 2 in Fig. 2, but rather bulges to the rear as indicated at 9 in Fig. 3. In this view, however, the edges of the sheet 3 are rather abrupt or clearly defined as shown at 10; whereas Fig. 4 differs only in that said edges are undercut as at 11. In any event the front face 5 stands below or behind the front face 6 of the cover.

In Fig. 5 I have shown how the sheet 3 may itself be dished or concave slightly on its front face, its edges 14 growing thinner or being beveled as shown, and I have also made use of this view to illustrate an adhesive between the sheet and the cover F, whether the former is dished or not, such

adhesive being of a material different from either the sheet or the cover. Most any ordinary glue or paste will do, so long as it is not liable to become soft under heat or moisture.

In Fig. 6 I have shown a section through a book whose front cover is waved slightly from its binding to its outer edge E, and in order that it will maintain the waves it is possible that this cover could be of light sheet metal. The drawing perhaps exaggerates the waves and the thickness of the entire article, but in the trough between these waves is located a panel P made in accordance with any form of my invention and secured in place in any suitable manner. Here again it is essential that the face of the panel shall lie behind a line drawn across the face of the front cover F at either side of the panel, or in other words that the panel should stand behind the highest points of the front face of the cover so that what is written on the panel will not ordinarily come in contact with contiguous objects in the wearer's pocket.

In Fig. 7 is shown an extremely simple embodiment of my idea which it might be possible to employ. Here the panel P is formed by stamping a depressed strip into and across the face of the cover F, which latter is of course thereby made a little denser at 2, and facing the front of the strip at 18 with some material which will readily take writing ink. This attribute is necessary to the facing of any panel described herein, whether that panel be a separate sheet attached to the cover by a separate and third element or composition, or directly attached to the cover, or whether the facing be merely printed on or indented into the cover so as to deface and obliterate the pebbles or other embossing thereon. Ordinarily I find that it is not sufficient to simply put pebbled material under high pressure to produce such a panel, because the pebbles within the panel although they are perhaps obliterated by the pressure, do not leave a good writing surface; and in fact the material of the cover itself whether subjected to this excessive pressure or not may not be a good writing surface, and it is essential to the successful carrying out of this idea that the panel P on the pass book may be written on with indelible ink by means of an ordinary pen.

Throughout the specification I have abstained from specifying materials and proportions of parts, and while I have styled this device a pass book it is obvious that the invention has a much wider range of use than on books of that specific character.

What is claimed as new is:

A book whose cover is unbroken and provided in its front with a depressed portion whose edges are beveled and merge into the face of the cover, said face having a poor

writing surface; combined with a sheet of material filling said depressed portion and adhering to the face of the same, its edges being undercut over said bevels, the thickness of said sheet being such that its entire surface lies in a plane behind that of the exposed surface of the cover.

In testimony whereof I affix my signature in presence of two witnesses.

WALTER ROYSTONE.
